UNITED STATES PATENT OFFICE.

WILLIAM H. BANZETT, OF BERGENFIELD, NEW JERSEY, ASSIGNOR TO AMERICAN LITHOGRAPHIC COMPANY, OF NEW YORK, N. Y., A CORPORATION OF NEW YORK.

PLATE-REGISTERING DEVICE.

Application filed October 28, 1919. Serial No. 333,972.

To all whom it may concern:

Be it known that I, WILLIAM H. BANZETT, a citizen of the United States, and a resident of Bergenfield, in the county of Bergen and State of New Jersey, have invented certain new and useful Improvements in Plate-Registering Devices, of which the following is a specification.

This invention relates to plate registering devices and has for its object to provide a device of the class specified adapted for accurately registering a plate in predetermined position throughout a series of machines, each of which is adapted for performing some function in preparing said plate for use as a printing plate, and for subsequently similarly registering said plate in a proof press and thereafter in a power press, from which quantity production may be had. By means of my improvements a plate may be carried through from the first step in its preparation as a printing plate to its final use in a printing machine, in accurate synchronism with the several machines or devices operating thereupon and therefrom.

In the present state of the art of producing printing plates, particularly plates for multicolor printing, a number of plates are required for each job, and the designs on those plates must be in accurate register with each other. Also, each of those plates goes through a number of mechanical operations in a variety of machines before it is ready to be printed from. After that, the plate must be put in a proof press and proved for color and details. Then, if said plate is one of a series of color plates, contributing to a multicolor design, it and its fellows must be printed from in sequence to produce a multicolor proof. Then these plates are used in a power or other press, if they are to be run "one up," or if required in multiple, the design is duplicated and the required number set up on one plate for each color, from which the edition is run. This obviously requires each plate to be set in register a large number of times.

Heretofore it has been customary to depend upon register lines on the plates for bringing those plates into suitable positions, respectively, in the various machines. This requires that each plate be individually tuned up for accurate positioning in each machine each time the plate is inserted. This is always an empirical operation and

open to constant error. Even if successful it is an expensive and time-consuming method.

By my improved device all experimental setting and adjusting is eliminated and the plate is placed in each of a plurality of machines to predetermined position with definite accuracy and reliability and in a minimum of time.

To these ends my improvements comprise features illustrated in their preferred embodiment in the drawings accompanying this specification, and the several groups of figures therein correspond as to applicability thereto, with the showing of several United States patents for inventions in machines for preparing plates for use as printing plates and for machines for printing from prepared plates, and include my copending application, Serial Number 312,813, filed July 23, 1919, for improvements in plate registering mechanisms. Those patents and that application have been selected as illustrative of the broad adaptability of my improvements to the general art of machines for making and using printing plates.

Figure 1 is a fragmentary plan view of my improvements as applied to the showing of United States Patent 954,290, issued on the invention of W. C. Huebner, April 5, 1910, and said figure corresponds with Fig. 4 of that patent. Fig. 2 is a sectional end view on line 2—2 of Fig. 1 and corresponds with Fig. 5 of said Huebner patent. Fig. 3 is another sectional end view on line 2—2 of Fig. 1, showing a modification of what is shown in Fig. 2. Fig. 4 is a plan view of my improvements as applied to the showing of United States Patent 1,015,681, issued on the invention of said Huebner, January 23, 1912, and said figure corresponds with Fig. 17 of that patent. Fig. 5 is a sectional elevation on line 5—5 of Fig. 4, and corresponds with Fig. 6 of said Huebner patent. Fig. 6 is a sectional elevation of my improvements on line 6—6 of Fig. 7, as applied to the showing of United States Patent 1,109,289, issued on the invention of said Huebner, September 1, 1914, and said figure corresponds with Fig. 2 of that patent. Fig. 7 is a sectional elevation on line 7—7 of Fig. 6 and corresponds with Fig. 1 of said Huebner patent. Fig. 8 is a plan view of my improvements applied to the showing of United States Patent 1,201,048, issued on the invention of said Huebner, October 10, 1916,

and said figure corresponds with Fig. 3 of that patent. Fig. 9 is a sectional elevation on line 9—9 of Fig. 8 and corresponds with Fig. 11 of said Huebner patent. Fig. 10 is a plan view of my improvements applied to the showing of United States Patent 1,051,590, issued on the invention of said Huebner, January 28, 1913, and corresponds with Fig. 3 of that patent. Fig. 11 is a sectional elevation on line 11—11 of Fig. 10 and corresponds with Fig. 2 of said Huebner patent. Fig. 12 is a sectional elevation of my improvements taken on line 12—12 of Fig. 13, and corresponds with Fig. 3 of my copending application, Ser. No. 312,813. Fig. 13 is a plan view of what is shown in Fig. 12 and corresponds with Fig. 2 of said copending application. Fig. 14 is a sectional elevation similar to a portion of what is shown in Fig. 12 and illustrating a modification thereof.

Referring now particularly to Figs. 1 and 2, my improvements comprise, first; registering means fixed to the plate, illustrated in their preferred form as a rail 3 fixed to one edge as 4 of plate 1. Said rail may be integral with said plate as shown in the section of Fig. 2, or said plate may have its edge 4 wrapped about the rail as in Fig. 14, or said rail may comprise two members 3^a and 3^b as in Fig. 3, between which the edge 4 of plate 1 may be clamped by screws 8, as in Figs. 12 and 13. Other modifications of fastening means between the plate edge and rail will be obvious to those skilled in the art but those shown are sufficient to illustrate this phase of my improvements. The essential feature is that said plate edge and rail be kept in their initial relation to one another throughout the manipulation of the plate during its preparation and use.

My improvements comprise, second; means, in one or more machines for preparing the plate as a printing plate, and in one or more machines for using that plate as a printing plate, for receiving and locating that plate, by means of its rail, in predetermined position. To these ends a seat or stop 10, Figs. 1 and 2, is provided in a fixed portion of the machine, as 13, or in a portion of the machine which may be shifted to various predetermined positions by precision screws or the like, as in Figs. 4 and 5 for instance.

This seat or stop may comprise a groove, against the forward edge 10 of which said rail 3 engages along its inner lengthwise face 3^c, Fig. 14, and said rail may be held in place by a suitable clamp as 14. For locating said rail endwise, opposite stops 15, 16, against which the opposite ends of said rail engage, respectively, are provided. One of said stops, as 15, is fixed and the other as 16, Fig. 1, may be adjustable, for forcing

said rail against stop 15, or said second stop 65 may be fixed also, as 16^a, Fig. 13.

In some cases it may be advantageous to provide that edge 17 of plate 1, opposite edge 4, with a rail 30, similar to rail 3, as in Figs. 4, 5 and 6, and to seat said rail similarly to 70 the seating of rail 3. In the showing of Figs. 4 and 5, the holding means for edge 17 of the plate is movably mounted so as to tension the plate by means of screws 18. In the showing of Fig. 6, the seats for rails 75 3 and 30 are both fixed, and after rail 3 is clamped into place the plate is tensioned by pressing rail 30 down into its seat by means of clamp 14^a.

In the showing of Figs. 8, 9, 10 and 11, 80 the rail is omitted from edge 17 of plate 1 and that edge is gripped between pivoted jaw 19 and clamp 20, and said jaw may be rocked on its pivot to tension said plate by means of screws 21.

From the foregoing description the adaptability of my improvements to a broad variety of local environment in machines for preparing and machines for using a printing plate will be apparent, and the means for accurately locating said plate in predetermined position in any one of said machines, and therefore the synchronizing of said plate in any selected series of said machines, will be clearly understood.

I claim:

1. In a plate registering device the combination of a plate, a rail fixed to one edge thereof, a seat for said rail, means for locating said rail in predetermined position lengthwise in said seat, means for locating said rail in predetermined position transversely in said seat, and means for holding the rail so located, in said seat.

2. In a plate registering device the combination of a plate, a rail comprising upper and lower members respectively between which said plate is clamped in fixed position, a seat for the lower member of said rail, means for locating said lower member in predetermined position lengthwise in said seat, means for locating said lower member in predetermined position transversely in said seat, and means for holding said lower member so located, in said seat.

3. In a plate registering device the combination of a plate, a rail fixed to one edge thereof, a seat for said rail, fixed means for locating said rail lengthwise in said seat and fixed means for locating said rail transversely in said seat.

4. In a plate registering device the combination of a plate, a rail fixed to one edge thereof, a seat for said rail, fixed means for locating said rail lengthwise in said seat, fixed means for locating said rail transversely in said seat and means for holding the rail so located, in said seat.

5. The combination with a press cylinder, of opposite holding members thereon, means for securing the opposite edges of a flexible sheet to said holding members, said sheet
5 having at one end thereof a fixed rigid part, and one of said holding members having a rigid part arranged to detachably engage the rigid part on the sheet to locate said sheet accurately in a predetermined position
10 lengthwise of the sheet on the cylinder, means for relatively moving said holding members to draw the sheet taut around the cylinder, and means for moving said rigid part on the sheet lengthwise of the cylinder
15 to a definite point to locate the sheet accurately in a predetermined position.

6. The combination with a press cylinder, of opposite holding members thereon, means for securing the opposite edges of a flexible sheet to said holding members, said sheet
20 having at one end thereof a fixed rigid part adapted to detachably engage one of said holding members, and said holding member having a rigid part with which said rigid
25 part on the sheet abuts to locate said sheet accurately in a predetermined position on the cylinder, means for forcing said abutting parts into contact, and means for relatively spreading said holding members to
30 draw the sheet taut around the cylinder.

7. The combination with a press cylinder, of a holding member thereon for one edge of a flexible sheet, a relatively stiff reinforcement on said sheet adjacent said edge
35 thereof, means for releasably connecting said reinforcement with said holding member, a stop on said holding member against

which a part of said reinforcement is adapted to abut in a direction crosswise of the sheet to accurately determine the position
40 of the sheet on the cylinder, and means for drawing the sheet taut around the cylinder.

8. The combination with a press cylinder, of a holding member thereon for one edge of a flexible sheet, a relatively stiff reinforcement on said sheet adjacent said edge
45 thereof, means for releasably connecting said reinforcement with said holding member, a stop on said holding member against which a part of said reinforcement is adapted to abut in a direction crosswise of the sheet to accurately determine the position
50 of the sheet on the cylinder, means arranged to engage said reinforcement and move it endwise against said stop, and means for drawing the sheet taut around the cylinder.
55

9. The combination with a press cylinder, of a holding member thereon for one edge of a flexible sheet, a relatively stiff reinforcement on said sheet forming a projecting shoulder parallel with said edge of the sheet, means for holding said shoulder against a holding edge on said holding member, a stop on said holding member against which a part of said reinforcement is adapted to abut in a direction crosswise of the sheet to accurately determine the position of
60 the sheet on the cylinder, means for holding said reinforcement against said stop, and means for drawing the sheet taut around the cylinder.
65

In witness whereof, I hereby affix my signature this 25th day of October, 1919.

WILLIAM H. BANZETT.
